REVOLVING DISTRIBUTOR

John Frank Baier, Cleveland, Ohio, assignor to
 Arthur G. McKee & Co., Cleveland, Ohio, a
 corporation of Delaware

Application June 20, 1947, Serial No. 755,935

5 Claims. (Cl. 214—37)

1

This invention relates generally to revolving distributors for blast furnaces and particularly to novel construction of small bell seats and novel means for sealing against escape of gases and solids from the furnace around the small bell seat.

In prior blast furnaces having revolving distributors the construction and arrangement of certain of the parts were not conducive to avoidance of wear or speedy replacement of worn parts. The small bell seat consisted of two semi-tubular parts connected together for about one-half of their length beginning at the lower end. It had a radially long flange extending outwardly from its upper end and this flange was connected at its outer edge to a ring gear which carried a track insert to run on supporting rollers. The hopper above the small bell seat was supported on the said flange. In this construction the bell seat flange afforded the full support for the bell seat proper as well as the hopper thereabove. Packing was disposed to engage the outer surface of the small bell seat immediately below the flange of that seat. Since the parts of the seat were not connected for the full length of the seat these parts did not always match perfectly to form a smooth outer surface, the misaligned edges wore the packing and caused gas leakage past it. Abrasive solids suspended in the furnace gases became embedded in the packing and caused wear of the outer surface of the seat, which wear was often extensive enough to permit escape of gases around the outside of the small bell seat. Since the packing was so close to the flange on the upper end of the small bell seat it could be replaced only with considerable difficulty unless the seat and superstructure were lifted. When the seat wore enough to require replacement, or when it was broken in use, the hopper, ring gear and certain of the rollers had to be removed from the furnace in order to remove the seat. Thus, the former construction necessitated the expenditure of considerable amounts of time to replace the small bell seat or the packing therearound.

In contrast to these prior constructions, those of my present invention are normally not rapidly worn and are readily and quickly replaced in whole or part when necessary. Whereas in the prior devices the wear and destruction of the parts was primarily due to abrasive solids accumulating in the packing glands and converting the packing into a grinding compound or mixture, in my assemblies the packing glands may be maintained substantially completely free from

2

abrasive solids so that the useful life of the parts engaging the packing thereby may be prolonged. I contemplate in this connection a grease reservoir as part of the packing gland construction and more or less constantly overflowing grease from the reservoir into the furnace so that solids accumulating in the inner opening of the reservoir will be continually ejected therefrom and not permitted to penetrate to a point where they could damage the bearing surfaces. Furthermore, by virtue of this invention it is possible, when the bearing parts are sufficiently heavy, to dispense with the conventional side rollers of blast furnace distributors which are provided to take up side thrusts and center the distributor.

Those skilled in the art will gain a further understanding of this invention upon referring to the drawings accompanying and forming a part of this specification, in which

20 Figure 1 is a fragmentary, side elevational view, partly in section of a revolving blast furnace distributor embodying one form of this invention;

25 Figure 2 is a side elevational view taken from line 2—2 of Figure 1;

Figure 3 is a sectional view taken on line 3—3 of Figure 1; and

Figure 4 is an enlarged sectional view of the sealing or packing means illustrated in Figure 1.

30 In general, the apparatus of this invention comprises a rotatable small bell seat, an annular girder supporting the seat and having a skirt defining an annular space with the seat, and packing means between the skirt and a fixed member to prevent the escape of blast furnace gases around the skirt.

The small bell seat 10 consists of two semi-tubular parts secured together throughout their full length and having outstanding flanges 11 at their top ends which rest upon and are supported by annular girder 12. The hopper 13 rests on the upper end of small bell seat 10 and is likewise supported by the annular girder 12. This annular girder 12 includes a depending skirt 14 at its inner edge which is spaced radially apart from seat 10 to define therewith an annular space 15. Girder 12 is provided at its outer edge with a track insert 16 positioned to run on supporting rollers 17 presently to be described. A ring gear 18 rests on the top of girder 12 at its outer edge and includes teeth 19 constituting an annular rack to engage with a driving pinion 20, a vertical abutment surface 21 to engage the smooth peripheries of side guide rollers

40

45

50

55

22, and a top track surface 23 to engage the under sides of rollers 24.

Rollers 17, 22 and 24 are rotatably carried by three columns 27 secured to and extending upward from the upper end of the furnace. Columns 27 are connected to each other and braced by means of three beams 28 and are disposed apart so that the centers of the beams are close to the sides of hopper 11. Rollers 17 and 24 are frusto-conical and in each column they are disposed with opposed surfaces sloping divergently inward toward the axis of seat 10 and hopper 11.

Means for preventing the escape of furnace gas between the fixed upper part of the furnace and the rotating girder comprises packing in the form of two packing rings 50 and 51 and a stuffing box 52, packing 53 and a packing gland ring 54 associated therewith. The ring 50 which depends from skirt 12 of girder 11 is bifurcated at its lower end, where it has inner and outer parallel, vertical walls defining an annular space. This ring is preferably made in several parts, for example four, for ready assembly and disassembly. The cooperating stationary ring 51 is likewise suitably composed of four quarter sections and is fastened to the furnace, extending upwardly into the said annular space between the inner and outer walls of ring 50. The outer wall 55 of ring 51 is detachable but when assembled therewith is disposed close to the outer surface of wall 56 of ring 50. Packing 53 is disposed between walls 55 and 56, and is compressed against both these members by stuffing box 52 which may be secured to the upper portion of ring 51 and packing gland ring 54 removably attached to box 52. Ring 54 is made up of four quarter sections while the box 52 is made up of six sections, four of which define arcs of 80 degrees and two of which define arcs of 20 degrees, to facilitate replacement of parts and inspection and cleaning of wall or ring 56. Lubricant may be forced into the spaces between the bifurcated walls of the sealing rings through a plurality of openings 57 and may fill the spaces, which then constitute a grease reservoir, to the extent that it may overflow the upper end of the inner wall of ring 51 and carry abrasive solids away from the bearings and back into the furnace. When box 52 and wall 56 are sufficiently heavy and strong they may constitute the distributor centering and side thrust bearing parts referred to above and side rollers 22 may be eliminated.

Packing 53 comprises a mixture of asbestos and copper wire impregnated with oil, or preferably grease, in order not to abrade the moving parts coming into contact with the packing.

When one of the parts such as packing ring 51, for instance, is to be replaced, it is only necessary to disengage from each other and the furnace the quarter-circular sections comprising the ring, similarly disengage the elements comprising stuffing box 52, disengage one of the sections of ring 50 and remove these parts from the assembly. A new ring 51 may then be installed and the stuffing box reassembled and replaced. The seat, hopper, driving means and supporting means of this assembly may thus be undisturbed and much time, effort and expense may thus be saved by comparison with replacement operations involved in the heretofore conventional assemblies of this general type.

Although I have described this invention with reference to one preferred, I contemplate other forms, as will be apparent from the appended claims. I have in mind, for instance, making

rings 50 and 51 in more or fewer than four sections and making stuffing box 52 in more or fewer than six sections, if worthwhile advantages may thereby be realized.

Having thus described the present invention so that those skilled in the art may be able to understand and practice the same, I state that what I desire to secure by Letters Patent is defined in what is claimed.

10. What is claimed is:

1. Sealing means for a revolving distributor of a blast furnace to prevent the escape of gases from the furnace around the small bell seat of said distributor comprising an annular skirt surrounding and connected to said seat for rotation therewith and defining an annular space with the seat, said skirt comprising a plurality of arcuately formed segments temporarily secured substantially fluid tightly together, and a stationary rigid metal packing ring surrounding said seat spaced therefrom and opposed to a portion of said skirt, said packing ring comprising a plurality of arcuately formed segments secured detachably together and fastened to and extending upwardly from the top of the furnace.

2. Sealing means for a revolving distributor of a blast furnace to prevent the escape of gases from the furnace around the small bell seat of said distributor comprising an annular skirt surrounding and connected to said seat for rotation therewith and defining an annular space with the seat, said skirt comprising a plurality of arcuately formed segments temporarily secured substantially fluid tightly together, a stationary rigid

30 metal packing ring surrounding said seat and spaced therefrom and comprising a plurality of arcuate segments secured together, and a stationary annular stuffing box surrounding said packing ring and cooperating therewith to define an annular space to receive a portion of said skirt, said stuffing box comprising a plurality of arcuately-formed segments temporarily secured substantially fluid-tightly together.

3. Sealing means for a revolving distributor of a blast furnace to prevent the escape of gases from the furnace around the small bell seat of said distributor comprising an annular skirt surrounding and connected to said seat for rotation therewith and defining an annular space with the seat, said skirt comprising a plurality of arcuately formed segments temporarily secured substantially fluid tightly together and having bifurcated lower edge portions defining an inverted channel extending substantially around said seat and spaced therefrom, and a stationary rigid metal packing ring surrounding said seat and spaced therefrom having a portion disposed in said channel to define with said bifurcated portion a passageway for a fluid, said ring comprising a plurality of arcuately formed segments secured detachably together and fastened to and extending upwardly from the top of the furnace.

4. Sealing means for a revolving distributor of a blast furnace to prevent the escape of gases from the furnace around the small bell seat of said distributor comprising an annular skirt surrounding and connected to said seat for rotation therewith and defining an annular space with the seat, said skirt comprising a plurality of arcuately formed segments temporarily secured substantially fluid tightly together, and a packing assembly cooperating with said skirt including a rigid metal packing ring having an annular upstanding portion, surrounding said seat and spaced therefrom, and an annular stuffing box cooperat-

60

65

70

75

ing with said packing ring to define an annular channel outside said ring in which to receive a portion of said skirt and to serve as a reservoir for packing grease, said packing assembly being provided with a plurality of spaced openings for introduction of packing grease into said annular channel, and said stuffing box comprising a plurality of arcuately-formed segments temporarily secured substantially fluid-tightly together.

5. Sealing means for a revolving distributor of a blast furnace to prevent the escape of gases from the furnace around the small bell seat of said distributor comprising an annular skirt surrounding and connected to said seat for rotation therewith and defining an annular space with the seat, said skirt comprising a plurality of arcuately formed segments temporarily secured substantially fluid tightly together and having free lower end portions spaced from said seat, and a stationary rigid metal annular stuffing box engaging said free lower end portions and centering and guiding said seat and cooperating with

the said end portions to define an annular space for receipt of solid packing, said stuffing box being fastened to and extending upwardly from the top of the furnace and comprising a plurality of 5 arcuately formed segments temporarily secured substantially fluid-tightly together.
